SYSTEMS FOR HANDLING ARTICLES INSIDE A FLUIDTIGHT CHAMBER

Laurent Urbain Chanut, Saint-Etienne, and Gabriel Roger Dardy, Saint-Priest-en-Jarez, France, assignors to Commissariat à l'Energie Atomique, Paris, France, a state administration of France

Application January 17, 1958, Serial No. 709,587

Claims priority, application France January 21, 1957

5 Claims. (Cl. 214—16)

The present invention relates to systems for handling articles inside a fluidtight chamber.

Such a system is particularly useful in nuclear energy plants where it is necessary to handle relatively heavy vessels which contain irradiated materials and which are temporarily stored up in chambers which must be fluidtight for obvious safety reasons.

Such a system must comply with the following conditions:

Inside the above mentioned chamber there must be only purely mechanical elements, this term excluding in particular motors for operating the system and the feed and control means of such motors;

The containers present in the chamber must be handled in such manner that they can be placed at any of a plurality of places defined by vertical sockets provided in the floor of the above mentioned chamber and distributed along several parallel rows.

The system according to our invention comprises a travelling crane including a bridge mounted to travel on runways transverse thereto and extending above the floor along two parallel vertical walls respectively of the chamber, and a carriage mounted to run along said bridge and supporting a hoisting mechanism arranged to operate a vertically movable hoisting member provided with hooking means for catching and holding the articles to be handled, a plurality of shafts extending in fluidtight fashion through the ceiling of the chamber so that the lower ends of said shafts located in said chamber are coupled with said bridge to control the traversing displacements thereof, the upper ends of said shafts being coupled with power means mounted on the top of said ceiling for driving them, a plurality of vertical shafts, extending in fluidtight fashion through said ceiling and in line with the above mentioned sockets respectively, being mounted slidably in said ceiling so that their lower ends can occupy, in said chamber, a neutral level or one of three different lower levels, said shaft lower ends carrying transmission means capable, when the shaft lower end is at one of said lower levels, of cooperating with means carried by said bridge for controlling the position of said carriage thereon, said vertical shaft being then driven in rotation by power means displaceable on the top of said ceiling so as to be able to be coupled with any of said vertical shafts, said transmission means being further capable, when said shaft lower end is at one of said lower levels, of cooperating with means carried by said carriage for placing said hoisting member exactly in line with the vertical shaft at the lower end of which said transmission means is mounted, said transmission means being also capable, when the shaft lower end is at another lower level, of coupling said hoisting mechanism with said shaft, and when the shaft lower end is at the third lower level, of having said hooking means operated by said shaft, power means displaceable on the top face of said ceiling being adapted to bring the shaft which is in line with the carriage successively to said

2

three lower levels and to drive it in rotation at each of said levels.

Preferred embodiments of the present invention will be hereinafter described with reference to the accompanying drawings, given merely by way of example and in which:

Fig. 1 is a transverse vertical section of the chamber provided with the system according to this invention.

Fig. 2 is a partial plan view in section on the line II—II of Fig. 1.

Fig. 3 is a longitudinal vertical section of the chamber with the system according to the invention.

Fig. 4 shows, on an enlarged scale, a vertical section of the carriage of the travelling crane, in the absence of a container.

Fig. 5 is a section on the line V—V of Fig. 4, with a container in position.

Fig. 6 is a plan view in section on the line VI—VI of Fig. 4.

Fig. 7 is a sectional view on the line VII—VII of Fig. 6.

Fig. 8 shows, on a still larger scale, a vertical section on the line VIII—VIII of Fig. 5.

Fig. 9 is a sectional view on the line IX—IX of Fig. 8.

25 Figs. 10 and 11 show, in plan view, the means for centering the hoisting mechanism with respect to the sockets of the chamber.

Fig. 12 is a vertical sectional view on the line XII—XII of Fig. 8.

30 Fig. 13 is a vertical section on the line XIII—XIII of Fig. 8.

Fig. 14 is a vertical section on the line XIV—XIV of Fig. 8.

The storing chamber 1, illustrated by Figs. 1 and 3, 35 includes vertical walls 2 and 3, a ceiling 4 and a floor 5.

In the floor 5 of said chamber there are provided several parallel rows of vertical sockets 6 located at equal intervals from one another and intended to accommodate cylindrical containers 7.

40 Two runways 8 (Fig. 3) are provided along the two vertical walls 3 for supporting, through rollers 9, the ends of the bridge or girder 10 of a travelling crane.

To each of the ends of this bridge 10 there is secured the upper portion of a chain 11 (Fig. 1) which passes, 45 at each end of the corresponding runway 8, round a sprocket wheel 12 driven from fixed power means 15, through a bevel gear 13 and a vertical shaft 14 which extends, in a fluidtight fashion, through ceiling 4.

The two chains 11 are simultaneously driven by two 50 power means 15 located in fixed position on the top of ceiling 4 so that the bridge, whatever be the direction of its displacement, is driven by the top portions of the chains, the lower portions of said chains being stretched by counterweights 16 guided in fixed frames 17 (Fig. 1).

55 Bridge 10 carries two rails or tracks 18 on which bear the rollers 19 of a carriage 20 (Fig. 3).

Carriage 20 is provided with a rack 21 fixed thereon (Fig. 2) the teeth of which mesh with cylindrical pins 22 (Figs. 2 and 3) mounted in diametrically opposed positions on discs 23 each fixed to the lower end of a vertical shaft 24. Said shafts 24 (Fig. 3), which are journaled in supports 25 rigid with bridge 10 and in line with each other, are driven, on each of said supports, through bevel gearings 26, horizontal shafts 27—28, and bevel gearings 29 interposed between shafts 28 and a vertical shaft 30. The top end of which is provided with a fork joint 31. The vertical plane in which shafts 24 are located is offset, with respect to the middle plane of carriage 20, by a distance equal to that existing between two adjacent rows of sockets 6.

70 The distance between two shafts 24 is such that there is

always at least one disc 23 in mesh, through its pins 22, with rack 21 (Fig. 2).

Carriage 20 (Figs. 1 and 3), which is in the form of a rectangular frame, carries, suspended therein through two pairs of rectilinear ball rolling tracks 33 and 34, a casing 32. These tracks, which are located one above the other, permit horizontal displacements of limited amplitude of casing 32 with respect to the carriage in two horizontal directions at right angles to each other.

The top portion 35 of casing 32 contains the hoisting mechanism.

A sleeve 36, mounted inside casing 32 (Figs. 4 and 5), is hanging through a ball socket joint 37 from a transverse member 38 itself pivoted about the axis 39 of a bar 40 to each of the ends of which there is fixed a chain 41.

This transverse member 38 is guided by means of two sleeves 42 along two upright members 43 which connect the bottom of casing 32 with the top part 35 thereof (Fig. 5).

Each of the two chains 41 meshes with a sprocket wheel 44 mounted in casing 35 and passes round a guiding roller 45 (Fig. 4), both of the chains having their other ends fixed to a cross member 46 acting as a counter-weight and the ends of which are guided along two rods 47 rigid with casing 32 (Fig. 4).

As shown by Fig. 9, each of the sprocket wheels 44 is rigid with a spur pinion 48 which meshes with a pinion 49, both of the pinions 49 being fixed on a shaft 50 rigid with a worm-wheel 51, itself in mesh with a worm 52 (Fig. 8).

Sleeve 36 (Figs. 4 and 5) carries three hooking levers 53 pivoted about horizontal axes 54 fixed with respect to said sleeve 36, said axes being at 120° to one another.

The hooks 55 of said levers 53 are adapted to engage under an inner flange 56 of a container 7.

The pivoting of levers 53 about their respective axes 54 is controlled by a device mounted under transverse member 38 and shown in plan view on Fig. 6.

This device includes a toothed disc 58 having its center in coincidence with the center of transverse member 38 and provided with three grooves 59 eccentric with respect to said disc. In each of these grooves is engaged a roller 60 mounted on the top end of one lever 53, respectively.

The teeth of disc 58 mesh with a pinion 61 slidable along a splined vertical shaft 62 extending between the bottom of casing 32 and the top portion 35 thereof, said shaft carrying, at its top end, a bevel pinion 63 (Fig. 8).

Pinion 61 (Fig. 4) is mounted between two discs of a slightly greater diameter which compel said pinion 61 to slide along shaft 62 when disc 58 is moving vertically.

Control of the hoisting chains 41 on the one hand and of hooking levers 53 on the other hand is obtained by means of the mechanism shown by Fig. 8.

The shaft of worm 52 carries a bevel pinion 64 which meshes with a bevel pinion 65 fixed on a hollow shaft 66 rigid with a circular plate 67.

On the other hand bevel pinion 63, carried by vertical shaft 62 which controls the hooking levers 53, meshes with a pinion 68 fixed on a horizontal shaft 69 carrying at its other end a second bevel pinion 70 in mesh with a pinion 71 rigid with a hollow shaft 72, coaxially mounted in the hollow shaft 66 and provided at its top end with a notched disc or plate 73.

Rotation of the two hollow shafts 66 and 72 is controlled by any of the vertical shafts 74.

As shown by Figs. 1 and 3, vertical shafts 74 are mounted in the ceiling 4 of chamber 1, each on the vertical of the center of a corresponding socket 6.

Each of said vertical shafts 74 is provided, at its top end, with a portion of square cross-section 75, adapted to be brought into engagement with a coupling member belonging to one of the two power means 76 and 77 displaceable on the top of the ceiling.

On the other hand, each of said vertical shafts 74 can be caused to slide with respect to said ceiling so as to

occupy any of a plurality of positions corresponding to different levels, these vertical displacements being controlled by a mechanism (not shown) included in each of the power means 76 and 77.

At its lower end, each of said shafts 74 is provided with coupling means constituted by a transverse bar 78 (Fig. 8) on which are mounted, about vertical axes 79, two rollers 80.

When shaft 74 is lowered, rollers 80 are brought into engagement, either (first case hereinafter referred to) with the means for controlling the displacement of carriage 20 on bridge 10, or (second case hereinafter referred to) with the hoisting mechanism.

In the first case, where shaft 74 is controlled by a power unit 76, rollers 80 are engaged in the fork joint 31 of shaft 30 (Fig. 3) and the rotation of shaft 74 is transmitted, through gearing 29, shafts 27, 28 and gearings 26, to shafts 24 either of which, in mesh through the pins 22 of its disc 23 with rack 21, controls the translatory displacements of carriage 20 along travelling bridge 10.

In the second case, where shaft 74 is controlled by a movable power unit 77, rollers 80 are engaged in notches 81 provided in an annular member 82 rigid with circular plate 67 (Fig. 8), and the rotation of shaft 74 is transmitted, through hollow shaft 66 and gearing 64-65, to worm 52, which controls the displacements of the hoisting chains.

However the combined movements of travelling bridge 10 and carriage 20 do not ensure in a perfect manner the necessary coincidence to be obtained between the vertical axis common to shaft 74 and the corresponding socket 6 on the one hand, and the vertical axis common to hollow shaft 66 and the hoisting sleeve 36 on the other hand.

This coincidence is ensured, after every displacement of travelling bridge 10 and/or of carriage 20, owing to the possibility of horizontal displacements of casing 32 due to the provision of rolling tracks 33 and 34.

Each of these rolling tracks includes a return device (Figs. 6 and 7) constituted by two antagonistic springs 83 bearing, on the one hand upon a projection 84 carried by a bar 85 which maintains the proper distance between two balls 33 or 34, and on the other hand against abutments 86, fixed with respect to the rolling track. The action of these springs tends to keep casing 32 in a mean center position with respect to carriage 20.

Above the top portion 35 of casing 32 is a frame 87 (Fig. 8) in which is provided an aperture 88 the shape of which is shown in plan view (and surrounded by cross-hatchings) in Figs. 10 and 11.

This outline permits of inscribing rollers 80 in frame 87 whatever be, within the limits permitted by the provision of rolling tracks 33 and 34, the position of casing 32 with respect to vertical shaft 74.

On Fig. 10, the vertical axis O of casing 32, and consequently of annular member 82, is shown in an eccentric position with respect to the axis of shaft 74.

When rollers 80 are inscribed in aperture 88, a rotation of 90° imparted to bar 78 by the movable power unit 77, brings rollers 80 into contact with the edge of aperture 88 and thus returns the axis O of annular member 82, which can move with respect to carriage 20 owing to the provision of rolling tracks 33 and 34, into coincidence with the axis of shaft 74, as shown by Fig. 11.

For this centering operation, shaft 74, and therefore bar 78, has been given by the movable power unit 77 a downward displacement A (Fig. 8), from the top position in which rollers 80 are at level X-X', that is to say above the plane in which move the parts supported by the travelling bridge and the carriage.

A further downward displacement B of bar 78 then permits of engaging the rollers 80 in annular member 82, and therefore of driving this member 82 in rotation,

this movement being transmitted to the hoisting chains. A third downward displacement *C* of bar 78 brings rollers 80 into a circular recess 89 provided at the lower end of annular member 82, whereby this annular member 82 ceases to be driven in rotation whereas bar 78 comes into engagement, through projections 105, with the notches of circular plate 73, the rotation movement of shaft 74 being then transmitted to pinion 61, which controls the hooking levers 53, by means of hollow shaft 72, pinions 71-70, horizontal shaft 69, pinions 68, 63 and shaft 62.

Safety means are provided in order to control the correct succession of the respective operations which are to be performed.

A rod 90 (Fig. 8), centered in hollow shaft 72, bears, at its lower end, on a roller 91 mounted at the end of a lever 92 (Fig. 13) which controls, by means of two toothed sectors 93 and 94, a shaft 95 which carries, at one of its ends, a pawl 96 intended to mesh with a notch 97 provided in the periphery of a disc 98 keyed on the shaft of worm 52 (Fig. 12). The other end of shaft 95 carries a flat member 99 provided with a notch 100 intended to engage on a sleeve 101 fixed on shaft 69 and having curved edges 102 concentric with shaft 95 (Fig. 14).

Rod 90 is controlled by the downward movement of bar 78. After a displacement of *A+a*, the vertical shaft 74 moves rod 90 downwardly so that, when rollers 80 are in engagement with annular member 82, pawl 96 is disengaged from disc 98 and permits the shaft of worm 52 to rotate, whereas, after a displacement *b* in addition to the downward displacement *B*, member 99 releases shaft 69 and permits the operation of hooking levers 53.

Bar 78 must not be allowed to move upwardly into the centering position as long as rollers 80, in engagement with annular member 82, are not disposed along the line which corresponds to the beginning or to the end of the hoisting movement. Accordingly, frame 87 carries two projections 103 intended to control the direction of bar 78 the upper wings of which are provided with corresponding notches 104 (Fig. 11).

The system above described is operated as follows:

Travelling bridge 10 and carriage 20 being in any given position, it is desired to displace a container 7 engaged in a given socket 6. The travelling bridge 10 is brought above a corresponding row of sockets by means of the two fixed power units 15 located on the side toward which the bridge is to be moved.

Carriage 20 is then moved transversely on bridge 10, by means of the movable power unit 76, to come above the socket that has been chosen. For this purpose, the movable power unit 76 is coupled with a vertical shaft 74 of the row of shafts adjoining that located above the bridge, this shaft being then lowered so as to bring rollers 80 into engagement with the fork joint 31 of the shaft 30 which controls the movements of translation of the carriage.

Of course, instead of first displacing the bridge and then the carriage, we might as well operate in the reverse order.

The movable power unit 77 is then coupled with the vertical shaft 74 now located above carriage 20.

The succession of operations controlled by said power unit 77 is then as follows:

Lowering of shaft 74 to bring rollers 80 into engagement with the centering frame 87; rotation of shaft 74 to perform the centering operation; lowering of shaft 74 to bring the rollers into engagement with annular member 82; rotation of shaft 74 to control the movement of the hoisting chains in the direction which causes sleeve 36 to move downwardly; stopping of the rotation and further lowering of shaft 74 to bring the projections 105 of arm 78 into engagement with the notches of plate 73; rotation of shaft 74 to control the engagement of the hooking levers with containers 7; stopping of the rotation and upward movement imparted to shaft 74 to

act subsequently upon annular member 82 in the direction which corresponds to an upward displacement of sleeve 36; stopping of the rotation in the position determined by pins 99; and finally upward movement of shaft 74 back to its initial position of rest.

The operations for placing a container in one of the sockets are the same, but effected in the reverse order.

It should be noted that any risk of a container being dropped during one of the operations is prevented by the fact that member 99 locks the hooking levers as soon as shaft 74 is lifted in order to be coupled with the annular member 82.

It may be necessary to cause a stream of air under pressure to flow through chamber 1. On Figs. 1 and 3, 15 we have shown, under sockets 6, a circuit 106 fed from mains 107 and channels 108, the fact of placing a loaded container 7 in a socket 6 having for its effect to operate a stopping member such as a valve (not shown) which enables air under pressure to enter chamber 1 and to cool 20 down the container 7 that has just been inserted into the socket.

In a general manner, while we have, in the above description, disclosed what we deem to be practical and efficient embodiments of our invention, it should be well understood that we do not wish to be limited thereto as there might be changes made in the arrangement, disposition and form of the parts without departing from the principle of the present invention as comprehended within the scope of the accompanying claims.

30 What we claim is:

1. For use in connection with a structure forming a fluidtight chamber including four vertical walls, two of which are parallel, a ceiling and a floor, said floor being provided with a plurality of vertical sockets disposed in 35 several parallel rows, a system for handling articles located in said chamber and adapted to fit in said sockets, which system comprises, in combination, runways extending above said floor along said two parallel walls respectively and at the same level, a bridge transverse to said 40 runways mounted to travel thereon, a carriage mounted to run along said bridge, a plurality of shafts extending in fluidtight fashion through said ceiling, so that the lower ends of said shafts are in said chamber, means for coupling the lower ends of said shafts with said bridge whereby rotation of said shafts produces transversing of said bridge, power means mounted in fixed position on the top face of said ceiling for driving said shafts from the outside of said chamber, a plurality of vertical shafts extending in fluidtight fashion through said ceiling, each of said last mentioned shafts being in line with one 45 of said vertical sockets respectively, each of said vertical shafts being slidable in said ceiling so that the lower end thereof can be positioned in said chamber either at a neutral level or at one of a plurality of lower levels, transmission means mounted at the lower end of each of 50 said vertical shafts, means carried by said bridge for controlling the position of said carriage thereon, said last mentioned means being arranged to cooperate with one of said transmission means when said last mentioned transmission means is at one of said lower levels, power means displaceable on the top face of said ceiling for being operatively connected with any of said vertical shafts to lower it to said last mentioned level and to 55 drive it, a hoisting member movable vertically in said carriage, hooking means for catching and holding said articles, said hooking means being mounted on said hoisting member, a hoisting mechanism mounted on said carriage for moving said hoisting member vertically with respect to said carriage, means carried by said carriage 60 to cooperate with one of said transmission means, when said transmission means is at one of said lower levels, for then placing said hoisting member exactly in line with the vertical shaft at the lower end of which said last mentioned transmission means is mounted, means carried by said carriage to cooperate with said last men- 65

tioned transmission means, when said transmission means is at another of said lower levels, for then coupling said hoisting mechanism with said transmission means, when said transmission means is at still another of said levels, for having said hooking means operated from said transmission means, and power means displaceable on the top face of said ceiling for being operatively connected with any of said vertical shafts to bring it successively to said last mentioned lower levels and to drive it in rotation at each of said levels.

2. A system according to claim 1 in which the transmission means mounted at the lower ends of said vertical shafts include a bar fixed to said shafts and extending on either side thereof at right angles thereto, and rollers mounted at the ends of said bar about vertical axes, said two rollers being diametrically opposed with respect to the corresponding vertical shaft.

3. A system according to claim 2 in which said hooking means are constituted by hooked levers pivoted to said hoisting member about respective horizontal axes, further including rolling means for movably supporting said member with respect to said carriage to permit limited horizontal displacements of said member with respect to said carriage, and a part rigid with said member forming a cam adapted to cooperate with said rollers and constituting the means for placing said member exactly in line with a vertical shaft.

4. A system according to claim 2 in which the means for coupling the hoisting means with a vertical shaft include a casing mounted in said carriage, a transverse member vertically movable in said casing and supporting said hoisting member, chains fixed to said transverse member, sprocket wheels, journaled in said casing and in cooperating engagement with said wheels, an annular member rotatable about a vertical axis with respect to said casing, said annular member being provided with notches adapted to cooperate with said rollers, and speed reducing gear means interposed between said annular member and said sprocket wheels.

5. A system according to claim 2 in which said hooking means are constituted by hooked levers pivoted to said hoisting member about respective horizontal axes, said means for having said hooking means operated from said transmission means including rollers carried by the upper ends of said hooked levers, a disc rotatable about a vertical axis with respect to said carriage and slidable vertically with respect thereto together with said hoisting member, said disc being provided with cam surfaces in cooperating engagement with said last mentioned rollers, and gear means slidable vertically with respect to said carriage for transmitting the rotating movement of said transmission means to said disc.
